TORCH OR LAMP

Robert A. Currie, Syracuse, N. Y., assignor to R. E. Dietz Company, New York, N. Y.

Application April 21, 1934, Serial No. 721,753

2 Claims. (Cl. 67—55)

This invention relates to improvements in flare torches or lamps of that sort which have no glass chimneys, globes or the like for protecting the flame, and which are commonly employed for lighting or signal purposes on construction jobs and for other out-of-door uses where they are exposed to the varying out-door weather conditions.

As commonly constructed, such torches are provided with a metal casing or flame guard which surrounds the upper end of the wick, providing a cover over the same, and has openings in its sides for the egress of the flame which, in the operation of the torch, flares out through the openings, and for the admission of the air to support combustion within the casing.

One purpose of my invention is to improve the construction of lamps or torches of the type mentioned.

Other objects of the invention are to provide desirable means of simple and inexpensive construction for removably locking or securing the burner on the torch font or body; also to provide a simple, inexpensive combined burner fastening and handle-attaching means for the torch; and also to provide a torch which has the features of improvement and advantage hereinafter described and set forth in the claims.

In the accompanying drawings:

Fig. 1 is a side elevation, on a reduced scale, of a torch of one construction embodying my invention.

Fig. 2 is a similar view of the torch as seen at right angles to Fig. 1.

Fig. 3 is a plan of the torch body without the burner and handle attaching plate.

Fig. 4 is a plan of the burner and handle attaching plate detached.

Fig. 5 is a sectional elevation on an enlarged scale on line 5—5, Fig. 2.

Fig. 6 is an elevation of the burner removed from the body.

Fig. 7 is a detail section on line 7—7, Fig. 5.

Fig. 8 is a sectional plan view of the burner casing on lines 8—8, Fig. 5.

Fig. 9 is a sectional plan view on line 9—9, Fig. 5.

The torch body or font 10 may be of any usual or suitable form and construction. As shown, it consists of a metal fuel receptacle provided in its top with an opening 11 for the passage of the wick and the reception of the wick tube or burner.

The burner in the construction shown comprises a wick tube 12 which is secured, as pres-

ently described, in the top opening of the font and a flame guard or casing 13 which surrounds and projects above the upper end of the wick tube. This casing is of cage-like formation having an annular bottom which projects laterally out from the wick tube below the upper end thereof, side walls and a top or cover 14. The casing forms a combustion chamber which is of much larger diameter than the diameter of the wick tube, the casing being preferably at least 10 approximately twice the diameter of the wick tube so that the cross sectional area of the combustion chamber is several times that of the wick tube and the wick 15 which extends from the font through the wick tube, with its upper end 15 exposed within this combustion chamber or casing 13. The sides of the casing 13 are provided with openings 16 equally spaced around the circumference of the casing and separated by solid wall portions or bars 17. Preferably these openings 16 are of greater height than width and extend from an elevation only slightly above the upper end of the wick tube 12 to the top or cover 14 of the casing, and preferably the combined area of the slots or openings 16 is substantially 20 equal to the combined area of the intervening solid wall portions 17.

In the preferred construction shown, the upper ends of the side bars 17 are bent outwardly, and the top 14 is secured as by spot welding, to 30 these outbent upper ends, the top or cover 14 being of larger diameter than the body of the casing so that it projects outwardly beyond the same and provides an overhanging shield or eaves of sufficient width to prevent the entrance 35 of rain into the burner through the side openings 16 even in a heavy driving rain storm. Preferably, the top 14 is of shallow conical form provided with circumferential slits, and the portions 18 of the top between its center and the slits 40 are offset upwardly so that openings 19 are formed in the top beneath the outer edges of said offset portions. These openings 19 are of substantial vertical height but very narrow horizontally so that while they provide openings in 45 the top through which flame and gases can escape from the combustion chamber, the upwardly offset portions 18 form guards which prevent appreciable entrance of rain through the openings 19.

The burner is detachably secured on the torch body 10 with the wick tube extending through the hole 11 in the top, preferably by a wing lock fastening formed by inclined wings 21 projecting laterally from the wick tube and adapted to 50 55

engage under complementary inclined locking members 22 on the torch body at opposite sides of the hole 11 so that by inserting the wings under these lock members and partially rotating the burner, the wings will wedge under the lock members and tightly clamp the burner on the body. Preferably the lock wings 21 are formed by circumferential projections on a collar 23 which is fixed on the wick tube below the 10 casing 13, as by a central down-turned flange on the collar which embraces and is welded to the tube, and the lock members 22 consist of circumferential projections struck up on a separate plate 24 which is permanently attached to the 15 top of the torch body, and has a central opening therein registering with the top hole in the body. A spacing sleeve 25 surrounds the wick tube between the collar 23 and the bottom of the casing 13, an air space being left between the 20 wick tube and the sleeve. This sleeve may be perforated as shown at 25a to allow ventilation for cooling the wick tube. The plate 24 is preferably seated in a shallow depression in the top of the body so that the top face of the plate will 25 be substantially flush with the surrounding top face of the body, the plate 24 being fixed in the depression as by spot welding. A packing washer or gasket 26 is confined in a depression in the top of the body by the plate 24, the locking 30 members 22 overhanging and being spaced slightly above the washer. When attaching the burner to the torch body, the wedging of the wings under the locking members will force the collar 23 on the wick tube down firmly against the washer, thereby forming a reliable oil-tight 35 joint between the burner and the top of the torch body.

The lock plate 24 is also preferably formed with opposite lateral arms, the outer ends of which are bent upwardly and perforated to form 40 attaching lugs 27 for the carrying bail or handle 28 for the torch. This handle bail 28 is of substantially U-shape having legs connected by a

cross bar 29, and the extremities of the legs are formed with hooks which pivotally engage in the perforated attaching lugs 27. The legs of the bail are preferably bent at 30 and the cross bar is curved laterally to substantially conform 5 with the curvature of the side of the body so that when the bail is swung down, the outer portions of the legs and the cross bar will lie close against the side of the torch body, and when the handle is swung upwardly into carrying position, the bends 30 in the legs are adapted to 10 rest against the top of the body and hold up the bail in a position for its cross bar to be grasped by the hand for carrying the torch. The handle can thus be folded down close against 15 the body to occupy the minimum space for shipping or packing purposes, but when raised to its upright position, is supported in this position 20 without the necessity for separate or additional supporting means.

I claim as my invention:

1. A torch comprising a fuel receptacle having an opening in its top, a burner having projecting lock wings and a combined burner and handle-attaching plate secured on said receptacle top and provided with lock members cooperating with said lock wings for removably fastening said burner on said receptacle, and said plate also having portions providing projecting lugs on the receptacle for the attachment of a carrying handle for said torch.

2. A torch comprising a fuel receptacle having an opening in its top, a burner registering with said opening, and a combined burner and handle-attaching plate secured on said top and surrounding said opening, said plate having parts cooperating with parts on said burner for removably attaching the burner to said receptacle, and said plate having oppositely extending arms provided with upwardly projecting portions 40 forming attaching lugs for a carrying handle for the torch.

ROBERT A. CURRIE.
